(57) **CLAIM**

The ornamental design for a USB camera, as shown and described.

DESCRIPTION

FIG. 1 is a top, front, left side perspective view of a USB camera, showing my new design;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right side perspective view of the USB camera of FIG. 1, shown in a folded configuration;

FIG. 10 is a top, front, right side perspective view of the USB camera of FIG. 1, shown in another folded configuration;

FIG. 11 is a top, front, right side perspective view of the USB camera of FIG. 1, shown in an alternate position;

FIG. 12 is an exploded top, front, right side perspective view of the USB camera of FIG. 1, shown in a second alternate position; and,

FIG. 13 is a top, front, right side perspective view of the USB camera of FIG. 1, shown in a disassembled configuration and in condition of use with a mounting clip disclosed in broken lines to illustrate an environment.

The broken lines depict portions of the USB camera that form no part of the claimed design. The broken lines showing the mounting clip in FIG. 13 depict environmental subject matter that forms no part of the claimed design. The break lines depicted with dot-dash broken lines in the drawings are included to show a symbolic break and the appearance of any portion of the article between the break lines forms no part of the claimed design.
